UNITED STATES PATENT OFFICE

EVERETT L. MOORE, OF LOS ANGELES, CALIFORNIA

DESIGN FOR A FAUCET

Application filed May 16, 1929. Serial No. 31,258. Term of patent 14 years.

To all whom it may concern:

Be it known that I, EVERETT L. MOORE, a citizen of the United States, residing at Los Angeles, in the county of Los Angeles and State of California, have invented a new, original, and ornamental Design for a Faucet, of which the following is a specification, reference being had to the accompanying drawing, forming part thereof.

Fig. 1 is a plan view of a faucet showing my new design.

Fig. 2 is a side elevational view.

Fig. 3 is an end elevational view.

Fig. 4 is a perspective view.

I claim:

The ornamental design for a faucet, as shown.

EVERETT L. MOORE.
